CONTROL INSTRUMENT

Gregor W. Kuntny, Philadelphia, Pa., assignor,
by mesne assignments, to Minneapolis-Honey-
well Regulator Company, Minneapolis, Minn.,
a corporation of Delaware

Application December 20, 1945, Serial No. 636,219

4 Claims. (Cl. 200—56)

1

The present invention relates to control instruments and more particularly a mercury switch control mechanism that is adaptable for use with a potentiometer type of instrument.

It is an object of the invention to provide a control instrument of a type that may be readily adjusted to control the condition being measured to any value within the range of the instrument. It is a further object of the invention to provide a relatively sensitive control system, or one in which the control switch can be thrown from one position to another by a movement of a condition responsive member through a relatively small percentage of the instrument scale.

It is a further object of the invention to provide a mercury switch control mechanism in which the switch is mounted on a carriage that is to be moved through an elongated path to a position proportional to the value at which the condition under control is to be maintained. Another part that is moved to positions corresponding to the changing value of the condition cooperates with the switch to operate it in one direction or the other as the condition varies above or below the control point.

It is a further object of the invention to provide a means to hold positively the control switch in the position to which it has been adjusted. This means comprises latch fingers cooperating with the switch support. The fingers are automatically released as the switch operating part moves into position when the switch has been operated. In another form of the invention the same means which serves to operate the control switch holds the switch in its adjusted position.

The various features of novelty which characterize this invention are pointed out with particularity in the claims annexed to and forming a part of this specification. For a better understanding of the invention, however, its advantages and specific objects obtained with its use, reference should be had to the accompanying drawings and descriptive matter in which is illustrated and described a preferred embodiment of the invention.

In the drawings:

Figure 1 is a wiring diagram of a potentiometer circuit;

Figure 2 is a perspective view of one form of the invention;

Figure 3 is a front view of a different form of the invention;

Figure 4 is a view taken on line 4—4 of Figure 3.

2

Figure 5 is a view of a still different embodiment of the invention, and

Figure 6 is a detailed view of a portion of Figure 5.

5 Referring first to Figure 1 there is shown a wiring diagram of a potentiometer circuit. In an instrument of this type there is provided a slidewire 1 across which a potential is placed by a battery 2. A portion of this potential is opposed by the E. M. F. developed by a thermocouple 3, and to this end the thermocouple is connected in the potentiometer circuit by means of a collector 4 that is attached to one of the thermocouple terminals. This collector is connected electrically with the slidewire 1 by means of a movable contact 5. The other thermocouple terminal is connected to the circuit through a switch 6 and an amplifier 7. When the contact 5 is so positioned along the slidewire 1 and collector 4 that there is no current flow in the circuit, the instrument is in balance. If, however, the thermocouple should be subjected to a change in temperature, the voltage produced thereby would change and a current flow would take place through the potentiometer circuit. This current flow is detected and amplified by the amplifier 7 to produce an energization of a rebalancing motor 8 in a direction depending upon the current flow in the circuit. The motor is mechanically connected to contact 5 to move this contact along slidewire 1 in such a direction that the thermocouple voltage is exactly opposed by the voltage drop across the slidewire. When contact 5 reaches this point along the slidewire 1, current will cease to flow in the circuit and the motor will again be deenergized so that the contact will remain still until a further change in thermocouple voltage takes place. At times it is necessary to recalibrate or standardize the potentiometer circuit. This is accomplished by moving a contact 9 of switch 6 to the right to disconnect the thermocouple from the circuit and to connect a standard cell 11 in its place. This standard cell is connected in the circuit and a suitable resistance 12 is simultaneously connected in the circuit around the amplifier 7. The standard cell produces a given voltage drop across a portion of the potentiometer circuit so that if this voltage is not exactly opposed by the voltage of the battery 2, a resistance 13 may be adjusted in suitable manner until the voltages are equal. Thereafter the contact 9 is moved to the left to again connect the thermocouple in the circuit. For further details of the potentiometer

circuit and the amplifier, attention is called to the copending application of Walter P. Wills, Serial No. 421,173, filed December 1, 1941, now Patent 2,423,540 issued July 8, 1947.

In Figure 2 there is shown one embodiment of the invention in which a mercury switch support is moved to a position corresponding to the temperature which it is desired to maintain, and in which a part movable by the motor 8 as it adjusts the slidewire is moved to adjust the switch mechanism.

There is provided a pair of supports 14 and 15 which may be attached to any suitable part of the instrument. These supports are joined by a channel member 16 and a shaft 17 which serve to mount and guide the various movable parts of the switch mechanism. Mounted for movement along the channel 16 is a control table 18. This table is generally U-shaped and is provided along the cross part of the U with spring 19 that engages the upper surface of the channel so that the control table may be held in its adjusted position and not move too freely from one position to the other. This control table is moved by a cable 21 that is attached to it by a cable clamp 20. The cable 21 passes over a pair of pulleys 22 and 24 that are suitably mounted at spaced points in the instrument. Channel 16 and bar 17 should be made as long as possible, and the supporting pulleys 22 and 24 should be just beyond the edge of these members so that the path of the cable along the channel will be straight. This does away with any tendency of the cable to lift the control table off the channel. The control table may be moved to any position along the channel 16 by means of a knob 25 that is attached to the pulley 22. Located adjacent the channel 16 is a scale 27 that has on it suitable indicating marks corresponding to the range of the instrument. Cooperating with the scale is a pointer 26 that is attached to table 18 and which extends in front of the scale to indicate the position of the control table and the temperature which is to be maintained.

It will be seen from the drawing that the rear part of the control table extends downwardly below the shaft 17. Journaled in the lower end of this portion is a shaft 28 that has attached to its front end a switch supporting member 29. Mounted upon this member is a mercury switch 31 that is held in position by a switch supporting clamp 32. The rearwardly extending portion of the shaft 28 has attached to it an arm 30 which is provided in its free end with a slot 33. Received by the slot is a pin 34 that projects from the end of a U-shaped tilting member 35 that is pivoted to the table 18 at 36. This member has projecting downwardly from its front side a portion 37 that is provided with a slot, the edges of which form projections 38 and 39.

The member 37 is tilted to move the mercury switch by a switch actuating member 41 which is fastened to a carriage 42 that is moved by the motor 8 as the latter is operated in response to potentiometer unbalance. Motion is imparted to this carriage to slide it along the shaft 17 upon which it is mounted by means of a cable 43 that is attached to the carriage by a cable clamp 44. The carriage is held in a proper position on shaft 17 by a roller 45 extending from its upper face, the roller being received by the channel member 16. This carriage may also be provided with a pointer that cooperates with the scale 27 to indicate the position of the carriage and therefore the value of the temperature being measured at any given

time. Movement of the carriage may also be used to move, in any conventional manner, a pen across a chart. The cable 43 passes around pulleys 46, one of which is located at each end of the shaft 17 and around a drive pulley 47, rotation of which serves to pull the cable in one direction or the other and thereby move the carriage 42. Pulley 47 is fastened to a shaft 48 that has on it a drive gear 49, the latter being driven by a pinion 51 on the shaft of the drive motor 8.

The operation of the device should be apparent from the above description. A short summary, however, will be given. The attendant of the instrument rotates knob 25 to move control table 18 to a position corresponding to the value at which the temperature under measurement and control is to be maintained. There is enough friction provided in this system by spring 19 to prevent accidental movement of table 18 along the channel 16 so that this table will remain in its adjusted position until it is again adjusted by an attendant. Thereafter, if the temperature being measured varies, carriage 42 will be moved relative to control table 18, and as it moves above or below this control table, the switch will be tilted in a direction to properly operate some temperature changing medium. As shown in the drawing, if the temperature varies in such a direction that the carriage 42 is moved to the right, operating member 41 will engage projection 39 on the part 35. The part 35 will then be moved in a counterclockwise direction to move the switch support in a clockwise direction and thereby open switch 31. Upon a return of the temperature to a value which will cause carriage 42 to move to the left, member 41 will engage projection 38 of the member 35 and thereby tilt the switch back to the position in which it is shown. The switch is connected by means of leads 52 to a terminal block 53. From this terminal block connections may be made with any suitable temperature controlling apparatus. The connections can be made in any conventional manner so that if the temperature is high, the temperature controlling medium will be reduced to thereby lower the temperature and vice versa.

In Figures 3 and 4 there is shown a different embodiment of the invention. This embodiment differs in construction from that previously described in that the control table is more rigidly mounted than that of the previous embodiment and in that it is provided with latches to hold the mercury switch in the position in which it is moved. There is also provided a frictionless mounting for the carriage that is moved by the potentiometer motor 8 so that the carriage may roll along rod 17 instead of being slid along that rod. Various parts corresponding to similar parts in Figure 2 have been designated by the same numeral used in that figure plus a letter.

In this case the supports 14a and 15a are extended downwardly below the rod 17a and have attached to their lower ends an inverted channel member 54. Received by the sides of this channel is a roller 55 that is attached by a bracket 56 to the downwardly extending portion of the control table 18a. Thus that table is held positively in a vertical position by the engagement of the upper portion thereof with channel 16a and by the engagement of the roller 55 with channel 54.

The switch actuating member that is mounted on shaft 36a is in this case designated 57 and has projecting from its left side in Figure 3 an arm 58 by means of which the mercury switch is operated when the member 57 is tilted around shaft

36a. The front portion of member 57 is generally Y-shaped with the two extending legs indicated by the reference numerals 59 and 61. The lower ends of each of these legs is provided with a forwardly extending portion, as is best shown in Figure 4. Cooperating with the forwardly extending portions of legs 59 and 61 are a pair of latch members 62 and 63 that are pivoted at 64 and 65 respectively on the control table 18a. Latch member 62 is provided with a portion 66 on its right end that is adapted to move to its dotted line position and engage the leg 59 of member 57 when the mercury switch is to be tilted in one direction. The latch 63 is similarly provided with an end portion 67 that is adapted to engage the leg 61 to hold member 57 in position when it is tilted in a direction opposite from the direction shown in the dotted lines. Each of the latch members is provided with a downwardly extending portion 68. The portion 68 on latch 63 lies directly behind that portion of latch 62 and accordingly cannot be seen in the drawings. The latches are biased by springs 69 and 71, respectively, in a direction so that they tend to engage and hold the legs of the switch actuating member 57. These springs could be omitted and the action of the latches be made dependent upon gravity if it is so desired.

The carriage which is moved by the potentiometer motor 8 in response to changes in the temperature measured is in this case designated by the reference numeral 72. This carriage is provided on each end with a pair of rollers 73 that engage the upper surface of the bar 17a and roll along this bar as the carriage is moved. The carriage is also provided with a roller 74 that is received by the sides of channel 18a. Rollers 73 and the roller 74 definitely locate the carriage and keep it in an upright position as it is moved through its path in the instrument. A more positive location of the carriage may be obtained, if desired, by providing a roller 75 which engages the lower surface of shaft 17a. This roller is mounted on a spring support 70 which in turn is fastened to the front of a downwardly projecting portion of this carriage. The force of spring 70 maintains roller 75 in engagement with shaft 17a and thereby also maintains each of the rollers 73 in engagement with the shaft.

Carriage 72 has attached to the upper portion thereof a block 76 which serves to engage legs 61 and 59 to tilt member 57. This block is formed near its front end with a cam 77 that cooperates with projections 68 on the latches to release these latches at such time as the carriage 72 is moving past control table 18a. It is noted that the cable 43 is attached to carriage 72 by a pair of cable clamps 80, one of which is located on each side of the projecting portion of spring 70.

Mercury switch 31 and its supporting clamp 32 are attached to a U-shaped switch supporting bracket 78 which in turn is pivoted on shaft 28 projecting forwardly from the lower portion of control table 18a. Bracket 78 is provided with an arm 79 extending to the left in Figure 3 by means of which the mercury switch may be tilted. The outer end of arm 79 is connected by a link 81 with the outer end of arm 58 and through this link motion of member 57 is transmitted to the mercury switch support. In this case the terminals 52 of the mercury switch are passed around shaft 28 from which they extend to the terminal block 53 which is suitably located in the instrument.

In the operation of this embodiment of the in-

vention, the control table 18a is positioned at a point corresponding to the value at which the temperature is controlled. Movement of the carriage 72 to the right or to the left of the table 18a in Figure 3 is used to operate the mercury switch. Suppose, for example, carriage 72 had been to the left of the position shown in full lines in Figure 3. If this were the case the parts on the table would be in their dotted line positions. Thereafter the change in temperature which caused carriage 72 to move to the right in Figure 3 produces the following operation. As the cam 77 moves beneath projections 68 of the latches, these latches will be lifted to the position shown in full lines in the drawing. This motion moves the end 66 of the latch 62 out of the path of leg 59 of member 57. Simultaneously the right edge of block 76 will engage the leg 59 and pivot the member 57 around shaft 36a. This movement continues until member 57 has been tilted counterclockwise in Figure 3 sufficiently for leg 61 to be behind the end 67 of latch 63. Member 57 will then be locked in position by latch 63 to hold the mercury switch in its new position until such time as the carriage 72 again moves to the left. It is noted that neither of the latches is effective when the carriage 72 is exactly centered with respect to table 18a, as is shown in full lines in the drawing. At this point, however, the use of the latches is not necessary since block 76 is made of such a size that it will simultaneously engage both of legs 59 and 61 of member 57 to hold that member in position without lost motion. When the temperature is at the control point, as it is with the position of the parts shown in full lines in the drawing, the control switch may be either opened or closed depending upon the arrangement that is used for the particular system under control. In each of the embodiments of the invention already described, the guide members are located in a horizontal plane. It will be readily apparent, however, that they could be located in a vertical plane if desired. In such a case the switch support would be rotated through 90° from the position shown. An arrangement in which the switch operating members are moved vertically will now be described.

In Figures 5 and 6 there is shown another embodiment of the invention. In these figures the same straight line movement of the part carrying the switch and of the part moved by the potentiometer motor is retained. In this case, however, a different structure is used for the control table and the carriage, which moves in response to temperature variations. The switch 31 is mounted on a support 83 which is rotatably attached to a control table taking the form of a longitudinally movable rack member 84. This rack is guided at its upper end in a suitable bearing as shown and is provided with a rod 85 extending from its lower end that is guided in a journal 86. The rack or control table 84 is moved upwardly and downwardly in order to adjust the control point of the instrument by means of a gear 87 in mesh with the rack and a pinion 88 that drives the gear. This pinion may be provided with a knob similar to knob 25 if so desired, or the pinion may be moved by a pointer 91 attached to the shaft thereof. This pointer cooperates with a scale 92 to indicate the control point for which the instrument is set. It is noted that there is provided a spring 89 attached at one end to the shaft of gear 87 and at its other end to a fixed point 90 in order to take up back-lash between the various parts. The leads from the mercury

switch 31 are wrapped around rod 35 in a helix before they are lead to the terminal block 53. In this manner the leads between the movable part of the mechanism and the terminal block are held in place and prevented from getting in the way of any of the movable parts of the instrument.

Support 83 is provided with two fingers 93 and 94 by means of which it is rotated around its pivot. Finger 93 cooperates with a flange 95 and finger 94 cooperates with a flange 96 that projects upwardly from the surface of a carriage taking the form of a second rack member 97. The manner in which these flanges are formed on the rack is best shown in Figure 6 in which it may be noted that one flange is in front of the other and that the upper end of flange 95 extends beyond the lower end of flange 96. This overlapping is equal to the distance between arms 93 and 94 where they engage the flanges. The rack or carriage 97 is moved upwardly or downwardly in accordance with changes in temperature that is being measured by the potentiometer instrument. To this end the rack teeth mesh with the teeth of a gear 98 which is fastened or geared to the shaft of the motor 8. Therefore, as the potentiometer motor rotates in response to potentiometer unbalance, the rack will be raised and lowered so that the flanges act on the fingers 93 and 94 of support 83 and tilt that support to work the control switch.

Some means is necessarily provided in instruments of this type to indicate the value of the temperature being measured. To this end there is provided a segment member 99 that is pivoted at 100. The lower surface of this segment is formed with gear teeth that mesh with the teeth of pinion 51 on the shaft of the potentiometer motor 8 or are driven by this pinion through suitable gearing. Attached to the shaft 100 of the segment member is a pointer 101 which cooperates with an indicating scale 102. It is noted that the two scales 92 and 102 are located side by side. If desired, however, by changing the position of the gearing, these two indicators could be made concentric.

In the operation of the device if the rack 97 has been moved upwardly so that the upper edge of flange 95 engages finger 93, the switch will be moved to the position shown, and the finger 93 will be held in its adjusted position by engagement between this finger and the top of flange 95. When the temperature has changed sufficiently for rack 97 to be lowered, the lower edge of flange 96 will engage finger 94 at the same time the upper edge of flange 95 moves below finger 93. To have continued downward movement of rack 97 will produce a clockwise rotation of switch support 83, thereby moving this switch to its other position. Therefore, there will be no lost motion in the operation of this switch as the rack 97 moves past the control point. The switch support will always be positively held in one position or the other or will be positively held as it is being moved between its two positions.

From the above description it will be seen that I have provided a novel type of control mechanism in which the operating parts of an instrument are moved in a straight line and parallel to each other. As the parts pass each other, the control switch will be thrown from one position to another. The point at which this passing will occur may be readily adjusted so that the point at which the control switch is operated is definitely located with respect to the scale of the instrument. Also because of the relatively long path

of travel of the control table and the carriage, the instrument is very sensitive. This is true since the movement of the carriage required to throw the control switch from one position to the other is only a small percentage of the range of the instrument.

While in accordance with the provisions of the statutes, I have illustrated and described the best forms of the invention now known to us, it will be apparent to those skilled in the art that changes may be made in the form of the apparatus disclosed without departing from the spirit of the invention as set forth in the appended claims, and that in some cases certain features of the invention may sometimes be used to advantage without a corresponding use of other features.

Having now described my invention, what I claim as new and desire to secure by Letters Patent is:

1. In a potentiometer having a measuring instrument sensitive to a variable under control and a motor responsive to the variations of said variable sensed by said measuring instrument, a control table mounted in said potentiometer for straight line movement, a cable secured to said control table, a manually operable knob having driving engagement with said cable for adjusting said control table, a control switch pivotally mounted on said control table, a switch actuating member pivotally mounted on said control table, and having driving engagement with said switch to move it from one position to another, and a carriage driven by the motor of the potentiometer in straight line movement into and out of engagement with said switch actuating member.

2. In a potentiometer having a motor responsive to the variations of a variable under control, means for actuating electric control switches including, a carriage mounted in said potentiometer for straight line movement, a cable driven by the motor of the potentiometer and connected to said carriage so as to drive it, a control table mounted in said potentiometer adjacent the straight path of motion of said carriage, a control switch pivotally mounted on said control table for movement into circuit-making and circuit-breaking position, and a switch actuating member pivotally mounted on said control table and having a portion extending into the path of motion of said carriage so as to be engaged thereby and having driving engagement with said switch to move it to one of its various positions when said actuating member is engaged by said carriage.

3. In a potentiometer having a measuring element sensitive to a variable under control and a motor movable in response to the variations of said variable as sensed by said measuring element, a pair of fixed supports, a pair of straight U-shaped channels secured to said supports, a straight rod secured to said supports, intermediate said channels, a control table slidably mounted on one of said channels, a flexible cable secured to said control table, a manually operable knob having driving engagement with said flexible cable for moving said control table for thereby setting the control point of the potentiometer, a switch pivotally mounted on said control table for movement between its circuit-making and its circuit-breaking positions, a switch actuating member pivotally mounted on said control table and having driving engagement with said switch for moving it between its circuit-making and its circuit-breaking positions, a

carriage having a pair of rollers pivotally mounted thereon and supporting said carriage for movement along said rod and having a third roller pivotally mounted thereon riding on the inside of one of said channels, a cable engaging with said carriage and driven by the motor of the potentiometer to move the carriage along the rod so that said carriage engages said switch actuating member and thereby actuates said switch between its circuit-making and circuit-breaking positions.

4. In a potentiometer having a motor movable in response to the variations of a variable under control, a guide supported in said potentiometer, a control table slidable along said guide, a cable secured to said control table, a manually operable knob having driving engagement with said cable for adjusting said control table, a spring engaging said control table and said guide and providing a yielding connection therebetween, a switch pivotally mounted on said control table,

a switch actuating member pivotally mounted on said control table and having driving engagement with said switch and having an extending portion, and a carriage mounted in said potentiometer for movement along a fixed path so as to engage the extending portion of said actuating member and thereby turn said switch about its pivot between its circuit-making and its circuit-breaking positions.

GREGOR W. KUNTNY.
